LIGHTING FIXTURE

Carl X. Meyer, St. Louis County, Mo., assignor to Day-Brite Lighting, Inc., St. Louis, Mo., a corporation of Missouri

Application June 4, 1956, Serial No. 41,760

Term of patent 14 years

(Cl. D48—23)

FIG. 1

FIG. 2

FIG. 3

FIG. 4

Fig. 1 is a perspective view of a lighting fixture embodying my new design;

Fig. 2 is a side elevational view of the lighting fixture, with a portion omitted for convenience of illustration;

Fig. 3 is a cross sectional view taken substantially along line 3—3 of Fig. 2; and

Fig. 4 is an elevational view showing the end of the lighting fixture opposite to that shown in Fig. 1.

I claim:

The ornamental design for a lighting fixture, substantially as shown.
